UNITED STATES PATENT OFFICE

EDWARD E. ROSE, OF EDGEWOOD, PENNSYLVANIA, ASSIGNOR TO WESTINGHOUSE ELECTRIC & MANUFACTURING COMPANY, A CORPORATION OF PENNSYLVANIA

CONTROLLER FINGER

Application filed November 21, 1925. Serial No. 70,535.

My invention relates to contact fingers, primarily designed for use in controllers.

The object of my invention, generally stated, is the provision of a contact finger that shall be simple and efficient in operation and readily and economically manufactured.

A more specific object of my invention is to provide for the free movement of the contact member so that it will accommodate itself to uneven surfaces.

It is also an object of the invention to provide for the setting of the contact finger to restrain the contact member against movement beyond a predetermined plane.

Other objects of the invention will, in part, be obvious and in part will appear hereinafter.

The invention accordingly is disclosed in the embodiment thereof shown in the accompanying drawings and comprises the features of construction, combination of elements and arrangement of parts which will be exemplified in the construction hereinafter set forth and the scope of the application of which will be indicated in the claims.

For a general understanding of the nature and objects of the invention, reference should be had to the following detailed description taken in connection with the accompanying drawing, in which:

Fig. 1, is a view in side elevation showing one embodiment of a device constructed in accordance with this invention;

Fig. 2 is a longitudinal sectional view showing features of the construction;

Fig. 3 is a view, partly in section and partly in elevation, showing details of construction;

Fig. 4 is a top plan view.

Referring now to the drawing, the reference character 10 indicates generally the base of the contact finger, which is provided with an inclined portion 11 that is adapted to be fastened to a board or other support usually provided in controllers or the like. As illustrated, the member 11 has an opening 12 provided therein for the reception of a bolt 12^a or other means that may be provided for attaching it to any support.

As shown, a substantially straight portion

13 is provided on the base 10 as a continuation of inclined portion 11 for the reception of a contact carrier to be described hereinafter. In order to facilitate the mounting of the contact carrier, a projection or lug 14 is provided on the outer end of the base and an opening 15 is formed near the point of juncture of the portion 13 with the board-engaging portion 11.

With a view to mounting a contact member or tip 16 so that it may move relatively to the base portion 13, a contact carrier 17 is movably mounted on the base. In this particular construction, the carrier 17 comprises a metal strip, the ends of which are curved downward. As will be observed, the curved portion on the outer end, or the end remote from the board-engaging portion 11 of the base, is considerably longer than the curved portion of the inner end, thus adapting it for the reception of the contact member 16.

The contact member 16 may be attached to the outer end of the contact carrier in any suitable manner, and in this particular construction the contact member is formed with an upwardly extending stud 18, which extends through an opening in the metal strip 17 and is spun over, thus giving a rigid connection.

In order to provide for the free movement of the contact member 16, the contact carrier 17 is pivotally mounted on the portion 13 of the base so that it may be freely oscillated about a longitudinal axis. As shown, the inner end of the carrier 17 is provided with a downwardly inclined projection 19, which is shaped to engage the opening 15 in the base. Formed in the contact carrier in a vertical portion near its outer end is an elongated opening 20 that is adapted to receive the projection 14 on the outer end of the base.

It will be observed that, by reason of the illustrated arrangement of parts, the straight portion of the contact carrier 17 is spaced from the outer end of the base portion 13. Thus the outer end of the contact carrier may be oscillated about the projection 14. In order to permit the inner end of the contact carrier to rock on the base, the inner end

is curved on each side of projection 19, as shown in Fig. 4. Therefore, it may be said that the carrier is supported on two pivots 14 and 19.

5 The contact carrier 17, in this particular construction, is retained in position on the base by means of a spring 21, which is mounted on a bolt 22 that is secured in the base portion 13 and extends through an opening 26 in the carrier 17. As shown, the opening 26 is made considerably larger in diameter than the bolt 22. Therefore, when the carrier is mounted in the manner described it may be oscillated about a transverse axis extending through the inner end of the plate 17, thus adapting it to ride over raised portions on a contact drum.

In order to set the contact carrier 17 and the contact member 16 in any desired position 20 relative to the base, a set screw 23 is adjustably mounted in the forward end of the contact carrier near the outer end of the base. The set screw may be locked in any position by means of a lock nut 24. As will be observed, the rounded end of set screw 23, if 25 adjusted to force the projection 14 out of its seat will serve as a pivot point for the contact carrier 17.

The contact member 16 may be connected 30 to a source of electrical current supply in a number of ways. However, in this particular embodiment of the invention a flexible conductor or shunt 25 is provided. As shown, the outer end of the conductor is 35 clamped between the outer end of the contact carrier 17 and the contact member 16. The body of the conductor extends beneath the base 10 and may be clamped in position by means of the bolt 12 that is provided for 40 attaching the base to its support.

In setting the contact finger for operation, the set screw 23 is adjusted to properly space the contact carrier 17 from the base 10, and to position the contact member 16 to ride on 45 the desired drum segment. If the drum segment has any raised portions, the contact carrier 17 may oscillate freely about a transverse axis extending through its inner end and the spring 21 continuously urges the 50 contact member 16 toward the drum segment.

If the drum segment over which the contact member 16 is moving is uneven laterally, the contact carrier 17 may freely oscillate 55 about a longitudinal axis extending through the projection 19 and the opening 20 or the end of the set screw 23. Thus it will be seen that the contact member 16 may move freely to accommodate itself to any unevenness in 60 a contact segment.

Since certain changes may be made in the above construction and different embodiments of the invention may be made without departing from the scope thereof, it is intended that all matter contained in the above

description or shown in the accompanying drawing shall be interpreted as illustrative and not in a limiting sense.

I claim as my invention:

1. A contact finger comprising, in combination, a base provided with a flat portion having a projection formed on the outer end, a contact carrier provided with a projection on its inner end, the inner end of the contact carrier being curved upwardly from the projection to provide a rocker, said base being provided with an opening to receive the carrier projection and said carrier having an opening for receiving the base projection, whereby the carrier may be mounted on the base to oscillate about its longitudinal axis, means for retaining the carrier in position on the base and adjustable means for setting the carrier relative to the base. 70

2. A control finger comprising a base having a projection formed on its outer end, a contact carrier having a projection formed on its inner end, the end of the carrier being curved to provide a rocker to seat on the base, said base being provided with an opening to receive the carrier projection and said carrier having an opening to receive the base projection whereby the carrier may be pivoted on the base to oscillate about a longitudinal axis, resilient means for retaining the carrier in position on the base and a set screw adjustably mounted in the contact carrier for setting the carrier relative to the base. 90

3. A contact finger comprising, in combination, a base, a carrier mounted on the base, said carrier being pivoted near its ends and having its body spaced from the base, one end of the contact carrier being curved to present a rocker face for seating on the base and the other end spaced from the base to permit oscillatory movement about its longitudinal axis, resilient means for retaining the carrier in position thereby to permit oscillatory movement about a transverse axis extending through the inner end of the contact carrier, and means for setting the forward end of the carrier relative to the base. 100

4. A contact finger comprising, in combination, a base having a projection extending therefrom, a contact carrier provided with a base engaging projection provided on one end, said end being curved upwardly from the projection, the base being provided with an opening to receive the carrier projection, the carrier being provided with a slot to receive the base projection, said carrier slot and base projection being disposed to guide and limit the movement of the carrier and resilient means disposed to continuously press the carrier toward the base thereby to retain the carrier in position. 115

In testimony whereof, I have hereunto subscribed my name this 17th day of November, 1925.

EDWARD E. ROSE.
